IGNITION APPARATUS

Edward B. Nowosielski, Bloomfield, N. J., assignor
to Eclipse Aviation Corporation, East Orange,
N. J., a corporation of New Jersey

Original application July 2, 1935, Serial No. 29,-
530. Divided and this application January 18,
1937, Serial No. 121,217

9 Claims. (Cl. 123—169)

This invention relates to spark-plugs, and more especially to spark-plugs for aviation engines. The severe service conditions which are imposed on spark-plugs for air-plane motors are familiar to those skilled in the art, as is also the importance of enclosing all parts of the high-tension current-carrying system by a continuous metallic shield to prevent interference with the reception of signals by adjacent radio receiving sets, and also to protect the exposed parts of the ignition system from detriment by the elements or otherwise.

The object of this invention is to provide a spark-plug, and more especially a shielded spark-plug, the construction of which is such as to prolong its life and to insure its effectiveness in such service, and to afford convenience and economy in manufacture.

The invention comprises novel features of great utility in spark-plugs, and novel combinations of elements making an improved spark-plug and an improved assemblage of the spark plug and its high-tension conductor. This application is a division of my application No. 29,530, filed July 2, 1935.

Some of the objects are to provide an improved core construction including novel methods of constructing and assembling the core; to provide improved heat deflecting and cooling means; and to provide improvements in the manner of insulating the current.

In the drawing,

Figures 1 and 2 are views partly in elevation and partly in section, each figure illustrating a somewhat different embodiment of the invention. In many respects both embodiments correspond to the disclosure in my copending application No. 16,882, filed April 17, 1935, and this is particularly true of the features indicated in elevation in the two embodiments; and where identical elements appear in the two embodiments they are designated by similar reference numerals.

First describing Figure 1, reference character 11 designates a metallic extension of the metallic body 10. As shown this part 11 extends upwardly to enclose the spindle 112 and the electrical connection between the same and the conductor which leads the high-tension current to the spindle. This shield extension is preferably in one piece with the attaching nut 5, though such unity is not necessary.

I provide a cooling and ventilating chamber 13 in the form of an annular space between the shield extension 11 and a long thin cylindrical metallic sleeve 14 having low thermal conductivity, and lined with a tube 15 formed of rolled mica constituting the wall of a second chamber 16 bounded at its lower end by the upper surface of the compressible metal gland 17, and at its upper end by a novel heat deflecting and sealing

assembly to be further described. It will be noticed that the spindle 112 extends upwardly to a point just above the end of the gland 17 and, due to the reduction in cross-sectional area at this point, and also by reason of the termination of the copper jacket 26 at this point, there is a tendency to cut off much of the upward flow of heat through the spindle 112 and to deflect the heat flow outwardly and radially into the copper gland 17 from which much of the heat is directly dissipated by the cooling blast circulating in chamber 13 by reason of the radial openings 32 in the metallic shell 11.

As a means of maintaining the mica stack 48 in the compressed condition and also applying radial pressure to hold the mica lining 15 of the inner metallic sleeve 14 in position, and at the same time effecting an additional path for the transfer of heat directly to the said sleeve 14 from which it may be radiated to the atmosphere by the cooling current of air flowing along the chamber 13 to and from the radial apertures 32, the embodiment shown in Fig. 1 includes cap and retainer elements 114 and 118 to permit the use of a method of assembly which results in a more secure positioning of the mica insulation. As shown, the method of assembly is to first insert the retainer 118 over the previously positioned mica parts 48 and 46 and due to the internal taper on the member 116 this act of inserting the said member will operate to tend to turn inwardly the upper extending end of the mica wrapper 46. After this has been done the cap 114 is inserted, the lower end of the stem thereof being slightly beveled to facilitate its passing the upper edge of the mica wrapper. Then as the stem descends it exerts a tightening action upon the upper portion of the mica wrapper 46 due to its having a slightly larger external diameter than that of the inwardly bent portion of the mica wrapper. When fully inserted the radially extending portion of the cap seats itself upon the annular ledge in the retainer 118 with its upper surface flush with the upper surface of said member, and thereby making it possible to apply a compressing force to both said elements which may be transmitted to the mica assembly 48 but without disturbing the upper end of the mica wrapper 46 due to the slight annular clearance indicated at 122.

The spring seat 113 of Fig. 1 rests upon an annular rim 126 formed by recessing the upper end of spindle 112. An asbestos disk 125 is inserted in this recessed end to aid in deflecting the heat flow away from spring 61.

In the embodiment of Fig. 2 the spindle 12 includes an upper thin walled section 131 and an upper upset end portion 132 of slightly thicker cross-section to provide additional strength along the surface of contact with the retainer ring 133.

and which receives a washer 154 against which the upper end 132 of the spindle is upset in the process of applying pressure to the parts 154 and 133 and thus to the washer 157 and mica assembly 48. Otherwise this construction resembles that of Fig. 1, including the use of a stem 158 having a flat base 156 resting upon the spring 61. These parts 133 and 154, when subjected to this upsetting pressure applied to the spindle top, act upon the washer 157 to compress the mica stack 48 and at the same time press against the expansion ring 161 to cause the latter to grip the mica lining 15 at a point approximately midway between its ends, this ring 161 being inserted and expanded against the lining 15 prior to the assembly of said tube within the shield extension 11.

By the process above described the cap assembly and spindle, that is, the parts 12, 156, 133 and 157 become a permanently integrated unit which, by reason of its extremely tight fit with the ring 161, is capable of transferring considerable heat from the upper part of the plug to the radiator tube 14. This heat transfer is accelerated by reason of the shunting effect of the asbestos heat barrier 159, there being a similar asbestos heat barrier shown in Fig. 1.

After the cap assembly has been secured by the upsetting process above described, coil spring 30 61 and stem 158 are inserted in position to contact the radially spread strands of the current conducting wire 66 when the latter is installed in place. Associated with the wire 66 is its covering 67 of insulating material, its outer metallic sheath 68, the swivel connection 69 soldered or otherwise secured thereto, and the detachable coupling nut 11, all of which are brought into assembled relationship with the parts previously described, by reason of the co-operating threads 40 at the top of shell 11.

Various changes, which will now appear to those skilled in the art, may be made in the form, details of construction and arrangement of the parts without departing from the spirit of the invention, and reference is therefore to be had to the appended claims for a definition of the limits of the invention.

What is claimed is:—

1. In a spark plug having a central spindle, a 50 wrapper of insulating material around the spindle, a stack of insulating discs surrounding said wrapper, and means for enclosing and protecting the upper edges of said wrapper, said means including a stack retaining member having a tapered bore fitting around said wrapper, and a second member having an externally tapered shank fitting within said wrapper, and also having a head above said wrapper, said head being supported by said stack retaining member.

60 2. A spark plug having the elements recited in claim 1, and characterized by the fact that the insulating wrapper is bent inwardly by the pressure of the stack retaining member upon the outer wall thereof, and is thereafter maintained in said bent condition under the oppositely directed pressures, first, of the stack retaining member, and secondly, of the externally tapered shank of said second member.

70 3. A spark-plug comprising the combination of a central spindle, a mica sleeve about said spindle, a body in which the spindle and its mica sleeve are fixed, a barrel extending upward from said

body above the spindle to form a socket for the insertion of an insulated high-tension conductor, a mica sleeve lining said barrel, a stack of mica washers occupying space between said mica sleeves and bearing on a shoulder of the body, and means above, and spaced from, the upper end of the spindle confining said stack.

4. A spark-plug comprising the combination of a central spindle, a sleeve about said spindle, a body in which the spindle and its sleeve are fixed, a barrel extending upward from said body above the spindle to form a socket for the insertion of an insulated high-tension conductor, a sleeve lining said barrel, a stack of washers occupying space between said sleeves and bearing on a shoulder of the body, and means above, and spaced from, the upper end of the spindle confining said stack.

5. In a spark plug having a central spindle, a sleeve of insulating material around the spindle, a stack of insulating discs surrounding said sleeve, and means for enclosing and protecting the upper end of said sleeve, said means including a stack retaining member having a tapered bore fitting around said sleeve, and a second member having an externally tapered shank fitting within said sleeve, and also having a head above said sleeve, said head being supported by said stack retaining member.

6. In a spark plug having a central spindle, a sleeve of insulating material around the spindle, a stack of insulating discs surrounding said sleeve, and means for enclosing and protecting the upper end of said sleeve, said means including a stack retaining member having a tapered bore fitting around said sleeve, and a second member engageable with said sleeve and supported by said stack retaining member, said two members co-operating to hold said sleeve in fixed relation thereto.

7. In a spark plug having a central spindle, a wrapper of insulating material around the spindle, a stack of insulating discs surrounding said wrapper, and means for enclosing and protecting the upper edges of said wrapper, said means including a stack retaining member having a tapered bore fitting around said wrapper, and a second member engageable with said wrapper and supported by said stack retaining member, said two members co-operating to hold said wrapper in fixed relation thereto.

8. In a spark plug having a central spindle, a wrapper of insulating material around the spindle, a body of insulating material surrounding said wrapper, and means for enclosing and protecting the upper edges of said wrapper, said means including a body engaging member having a tapered bore fitting around said wrapper, and a second member having an externally tapered shank fitting within said wrapper, said two members cooperating to hold said wrapper in fixed relation thereto.

9. In a spark plug having a central spindle, a sleeve of insulating material around the spindle, a body of insulating material surrounding said sleeve, and means for enclosing and protecting the upper end of said sleeve, said means including a body engaging member having a tapered bore fitting around said sleeve, and a second member supported by said body engaging member, and cooperating therewith to hold said sleeve in fixed relation thereto.
